Atlanta, Georgia

UNITED STATES PATENT OFFICE.

WALTER C. KRETSCHMER, OF CHICAGO, ILLINOIS.

SPARK PLUG.

Application filed January 27, 1921. Serial No. 440,346.

To all whom it may concern:

Be it known that I, WALTER C. KRETSCHMER, a citizen of the United States, residing at Chicago, in the county of Cook and State 5 of Illinois, have invented a new and useful Improvement in Spark Plugs, of which the following is a specification.

This invention relates to improvements in spark plugs, and more especially to that 10 kind of a spark plug adapted for use in connection with the ignition of an internal combustion engine. It is of the type of plug adapted to produce two spark gaps in order to make the ignition of the confined gases 15 in the engine cylinder more certain.

Among the features of my invention is the provision of means by which the terminals at the end of the plug may be readily cleaned without removing the plug from 20 the engine cylinder. The other features of my invention will appear more fully as I proceed with my specification.

In that form of plug embodying the features of my invention shown in the accompanying drawings, Figure 1 is a vertical sectional view of my improved plug, Figure 2 is a bottom plan view thereof, Figure 3 is a vertical sectional view of the shell of the plug only taken as indicated by the line 3 of 30 Fig. 1, Figure 4 is a plan view of one of the gaskets used in the construction of the plug, Figure 5 is a horizontal sectional view of the insulating core of the plug taken as indicated by the line 5 of Fig. 1, and Figure 6 is a view in side elevation of the end of the core as shown in Fig. 1.

As shown in the drawings, the plug consists of a casing 4, of any desired pattern and construction, formed at one end with the 40 threads 5 adapted to engage threads in a hole in a cylinder of an engine in the usual manner. A shoulder 7 is formed in the casing 4, and at the outer end of the latter it is enlarged and threaded on the inside, as at 45 8, to receive the threaded portion 9, of a nut 10. A core 11, of porcelain, or any other suitable insulating material, is fitted in the casing 4 as shown. The insulating core 11 has near its center an enlarged cylindrical 50 part indicated by 80, forming the lower flange 12 and upper flange 13. The core 11 is also provided with an axial central opening 14. The core 11 is placed in the casing with the flange 12 abutting against the 55 shoulder 7, a gasket 81 being interposed therebetween. The nut 10 is screwed into

place with its lower edge abutting against a gasket 83 which rests on top of the flange 13. It is obvious that by screwing down the nut 10 the core 11 will be held firmly in 60 place in the casing. The lower or inner end of the core 11 is tapered as indicated by 85.

Extending through the hole 14 in the core 11 is a metal spindle 15 having attached to its upper end in any suitable manner the 65 lock nuts 86 and binding post 87 of ordinary construction, adapted for attaching a wire thereto. The lower end of the spindle 15 is curved and bent upwardly to form an electrode 19, the end of the same being indicated 70 by 119. The extreme inner or lower end of the core 11 is slightly enlarged to form a flange or button 89 having at one point on its periphery a wedge shaped projection indicated by 90. Surrounding the flange or 75 button 89 is a metal band or electrical conductor 20 having its edges slightly bent or crimped in around the button as indicated by 91 in order to prevent displacement. Embedded in the inner end of the casing 4 80 is another electrode 21 comprising a U-shaped wire having its ends 92 bent upwardly and inserted in the edge of the casing 4.

On the inside of the casing 4, projecting 85 upwardly from the shoulder 7 is a short pin 93, and the flange 12 on the core 11 is provided with a recess 94 adapted to accommodate the pin 93. The recess 94 extends slightly more than 180 degrees around the 90 periphery of the flange 12. The gasket 81 is also provided with a notch 95 adapted to accommodate the pin 93. It will be seen that by this construction, when the nut 10 is slightly loosened, the core 11 may be rotated 180 degrees, the pin 93 acting as a stop 95 against the two ends of the recess 94.

The electrode 19 is firmly fixed in the core 11 and has its end 119 bent upwardly and away from the projection 90. The recess 94 100 in the flange 12 is so formed with respect to the projection 90 on the end of the core 11, and the pin 93 is so located in the casing 4 that when the parts are in the position shown in Fig. 2 the pin 93 will be against one end 105 of the recess 94; and such recess will permit rotation of the core 11 for 180 degrees in a clockwise direction (as viewed in Fig. 2) permitting rotation of the projection 90 so that the metal band 20 where it covers this 110 point as indicated by 99 will rub or brush against the electrode 21, as

indicated by the broken lines. The end 119 of the electrode 19 is turned upwardly and away from the point 90. It is obvious that by this construction rotation of 5 the core 11 cannot be made to cause contact between the electrodes 19 and 21; such rotation being permitted only through 180 degrees.

In the operation of my improved plug, 10 one of the high tension wires of the ignition circuit is connected to the terminal 87 and the other is grounded to the engine in the usual manner. The core 11 is then rotated until the pin 93 stops rotation against either 15 end of the recess 94. When in this position the parts will be as shown in Fig. 2. The nut 10 is then tightened down causing the parts to be securely fixed in position. In use, a spark gap is formed between the end 20 119 of the terminal 19 and the band 20, and another spark is formed between the band 20 and the terminal 21. It will be seen therefore that two distinct and separate sparks are formed. If the terminal 21 becomes 25 dirty or carbonized, the nut 10 may be slightly loosened to permit rotation of the core 11, and such core may be then rotated back and forth causing the point 99 to rub or wipe the electrode 21 thus cleaning it. 30 After this cleaning operation has been performed, the core 11 is rotated as described

above, until the pin 93 acts as a stop against one end or the other of the recess 94, whereupon the nut 10 is again tightened to fix the parts firmly in place.

While I have shown and described certain embodiments of my invention, it is to be understood that it is capable of many modifications. Changes therefore in the construction and arrangement may be made 40 without departing from the spirit and scope of the invention as disclosed in the appended claim, in which it is my intention to claim all novelty inherent in my invention as broadly as possible in view of the prior art.

45 What I claim as new, and desire to secure by Letters Patent is:

A spark plug comprising a casing, a rotatable insulating core therein, an electrode projecting from the core, a second electrode 50 projecting from the casing, an electrical conductor attached to the core and insulated from both of the aforementioned electrodes, such conductor having a point adapted to rub the electrode on the casing upon rotation of the core, and means for limiting the rotation of the core to prevent contact between the first mentioned two electrodes.

55 In testimony whereof, I have hereunto set my hand and seal this 25th day of January, 1921.

WALTER C. KRETSCHMER. [L. S.]
